P. D'H. DRESSLER

OPEN FIRE KILN

Filed Aug. 26, 1924

Patented Dec. 6, 1927.

1,651,380

UNITED STATES PATENT OFFICE.

PHILIP D'HUC DRESSLER, OF CLEVELAND, OHIO, ASSIGNOR TO AMERICAN DRESSLER TUNNEL KILNS, INC., OF CLEVELAND, OHIO, A CORPORATION OF NEW YORK.

OPEN-FIRE KILN.

Application filed August 26, 1924. Serial No. 734,167.

My present invention relates to a continuous tunnel kiln heated by means of combustion chambers or fire boxes disposed at intervals along the length of the kiln at the 5 sides of the latter and discharging hot products of combustion directly into the kiln chamber; and the general object of the invention is to provide such a kiln with improved means for distributing the heat to 10 the goods moving through the kiln, and in particular to avoid the intense local overheating of the goods in front of the fire boxes which is characteristic of kilns of the type referred to and is objectionable in the 15 case of many kinds of wares treated in such kilns.

The various features of novelty which characterize my invention are pointed out with particularity in the claims annexed to 20 and forming a part of this specification; but for a better understanding of the invention, its advantages and specific objects attained 25 with its use, reference should be had to the accompanying drawings and descriptive matter in which I have illustrated and 30 described a preferred embodiment of my invention.

Of the drawings:

Fig. 1 is a diagrammatic plan view of a 35 tunnel kiln with parts broken away and in section;

Fig. 2 is a partial section on the line 2—2 of Fig. 1;

Fig. 3 is a partial section on the line 3—3 35 of Fig. 2; and

Fig. 4 is a partial section on the line 4—4 of Fig. 2.

The kiln A shown in the drawings comprises a preheating zone A', a furnace or 40 firing zone A², and a cooling zone A³. Distributed along the two sides of the firing zone portion of the kiln are combustion chambers E. The latter may be of any usual or suitable form and, as shown, are provided 45 with grates E² for the combustion of solid fuel but may equally well be heated by the combustion of oil or gas. Each combustion chamber or fire box E discharges hot products and burning gases into the kiln chamber 50 through a corresponding throat or hot gas outlet E'. In so far as above described the kiln is of a well known type.

In accordance with the present invention the hot gases issuing from each combustion 55 chamber E through the discharge outlet or

throat E' of the latter do not pass directly into the kiln chamber but into a narrow chamber D at the side of the kiln chamber. As shown, there is a chamber D in front of each fire box. The chambers D at each side 60 of the kiln are located between the side wall of the kiln structure proper and a vertical baffle wall C extending along the length of the firing zone and are separated from one another by narrow partitions d. Advantageously also the walls C are provided with vertical thickened wedge-like imperforate portions C² at their outer sides, one directly in front of each combustion chamber throat E'. These wedge-like portions C² deflect the 70 heating gases from each combustion chamber into the portions of the corresponding chamber D at each side of the axis of the latter, and by reason of their thickness reduce the heat radiation from the corresponding portions of the wall C, which otherwise might be excessive. The upper edges of the chamber D advantageously terminate some distance below the roof arch a 75 of the kiln structure proper and are closed 80 by suitably shaped tiles F. To prevent undesirable longitudinal flow of the kiln atmosphere through the space between the tiles F and the roof arch suitably located transverse baffles G are provided. The heating 85 gases supplied to the chamber D are discharged from the latter into the kiln chamber through suitably disposed ports C' formed in the walls C. These heating gases after imparting their heat to the wares K, 90 moved through the kiln on the usual kiln cars I, are withdrawn from the kiln adjacent its exit end as by means of outlets A' communicating with a conduit H' running to a draft creating device shown as a stack H. 95

With the described construction, the ported walls C prevent the direct radiation of heat from the intensely hot combustion chambers against the wares K, and form means for properly distributing the supply 100 of heat along the entire length of the firing zone A² of the kiln. The construction obviously permits whatever arrangement of the ports C' is adapted to secure the desired distribution of heating gases. In general, 105 it is desirable to admit the greater portion of the heating gases to the kiln chamber adjacent the bottom of the space traversed by the wares K and for this reason the ports C' may be more closely spaced adjacent the 110

bottom of the goods pathway, as shown in Fig. 4, than at higher levels. The lowermost ports C' may well be located so that the gases discharged by them are directed 5 into the distributing channels I' ordinarily formed in the refractory top portions of kiln cars I immediately below the work supporting surface of the latter. The uniformity of heat distribution obtainable with the invention 10 obviously permits of a rate of heat supply to the kiln which is practically a maximum in the case of wares subject to injury by local overheating. In consequence, the use of the invention tends to increase kiln 15 capacity as well as to an improved product, in firing wares subject to injury by local overheating.

While in accordance with the provisions of the statutes I have illustrated and described the best form of my invention now known to me, it will be apparent to those skilled in the art that changes may be made in the form of the apparatus disclosed without departing from the spirit of my invention 25 as set forth in the appended claims, and that certain features of my invention may sometimes be used to advantage without a corresponding use of other features.

Having now described my invention what 30 I claim as new and desire to secure by Letters Patent is:

1. In an open fired tunnel kiln provided with fire boxes distributed along the length of the firing zone portion of the kiln at each 35 side of the latter, the improvement which consists in walls between the goods pathway through the kiln and the kiln side walls and uniting with the latter to form chambers receiving the heating gases from the fire boxes, 40 the first mentioned walls being formed with perforations in their lower portions distributed along a substantial portion of the length of the kiln through which the major portion of the heating gases pass into the 45 lower portion of said pathway.

2. In an open fired tunnel kiln provided with fire boxes distributed along the length of the firing zone portion of the kiln, the improvement which consists in perforated 50 walls between the goods pathway through the kiln and the kiln side walls and uniting with the latter to form chambers receiving the heating gases from the fire boxes and distributing them along the length of the kiln, said walls comprising imperforate 55 portions one in front of each fire box.

3. In an open fired tunnel kiln provided with fire boxes distributed along the length of the firing zone portion of the kiln, the improvement which consists in perforated walls 60 between the goods pathway through the kiln and the kiln side walls and uniting with the latter to form chambers receiving the heating gases from the fire boxes and distributing them along the length of the kiln, said walls 65 comprising imperforate portions one in front of each fire box wedge shaped in horizontal cross section to deflect the heating gases from the fire box longitudinally of the kiln 70 in opposite directions.

4. In an open fired tunnel kiln provided with fire boxes distributed along the length of the firing zone portion of the kiln, the improvement which consists in perforated walls between the goods pathway through the kiln and the kiln side walls and uniting with the latter to form chambers one in 75 front of and receiving the heating gases from each fire box and distributing said gases along the length of the kiln, and vertically extending brick work partitions one between each two adjacent chambers.

5. In an open fired tunnel kiln provided with fire boxes distributed along the length of the firing zone portion of the kiln, the improvement which consists in perforated walls between the goods pathway through the kiln and the kiln side walls and uniting with the latter to form chambers receiving the heating gases from the fire boxes and distributing them along the length of the firing zone of the kiln, and brick work spaced 80 away from the kiln roof and closing the upper ends of said chambers.

6. In an open fired tunnel kiln provided with fire boxes distributed along the length of the firing zone portion of the kiln, the improvement which consists in perforated walls between the goods pathway through the kiln and the kiln side walls and uniting with the latter to form chambers receiving the heating gases from the fire boxes and distributing them along the length of the firing zone of the kiln, brick work spaced 90 away from the kiln roof and closing the upper ends of said chambers, and transverse baffles between said brickwork and kiln roof.

Signed at Cleveland, O., in the county of Cuyahoga and State of Ohio, this 23rd day 100 of August, A. D. 1924.

PHILIP D'HUC DRESSLER.
